CLAIM

We claim the ornamental design for a handle apparatus, as shown and described.

DESCRIPTION

FIG. 1 is a perspective view of a handle apparatus embodying the present invention;

FIG. 2 is a first side view of the handle apparatus;

FIG. 3 is a rear view of the handle apparatus;

FIG. 4 is a top view of the handle apparatus; and,

FIG. 5 is a bottom view of the handle apparatus.

The broken lines shown in the drawing are for illustrative purposes only and form no part of the claimed design.
